DESIGN FOR A FRAME FOR A TRICYCLE

William I. Smith, Perrysburg, Ohio, assignor to
The Hettrick Manufacturing Company, Toledo,
Ohio, a corporation of Ohio

Application February 10, 1945, Serial No. 117,869

Term of patent 14 years

(Cl. D34—15)

To all whom it may concern:

Be it known that I, William I. Smith, a citizen of the United States and a resident of Perrysburg, Wood County, Ohio, have invented a new, original, and ornamental Design for a Frame for a Tricycle, of which the following is a specification, reference being had to the accompanying drawing, forming a part thereof.

In the drawing:

Figure 1 is a front perspective view of a frame for a tricycle showing my new design;

Figure 2 is a top plan view; and

Figure 3 is a rear end elevation.

I claim:

The ornamental design for a frame for a tricycle, as shown.

WILLIAM I. SMITH.
